UNITED STATES PATENT OFFICE.

HENRY K. SANDELL, OF CHICAGO, ILLINOIS, ASSIGNOR TO MILLS NOVELTY COMPANY, OF CHICAGO, ILLINOIS, A CORPORATION OF ILLINOIS.

SELF-PLAYING MUSICAL INSTRUMENT.

Application filed July 15, 1922. Serial No. 575,195.

To all whom it may concern:

Be it known that I, HENRY K. SANDELL, a citizen of the United States, residing at Chicago, in the county of Cook and State 5 of Illinois, have invented a new and useful Improvement in Self-Playing Musical Instruments, of which the following is a specification.

The present invention relates to improvements in self-playing stringed instruments of the viol class and more particularly to devices in connection therewith for producing staccato effects and for effecting the timely removal of the bows or sounders 10 from the strings. It will be fully understood from the following description, illustrated by the accompanying drawings, in which—

Figure 1 is a plan view showing a device 20 embodying the present invention in connection with the bows or sounders of a viol type instrument, for example, a violin;

Figure 2 is a side elevation of the same device; and

Figure 3 is a sectional view on the lines 25 3—3 of Figure 2 viewed in the direction of the arrows.

In the embodiment of the device shown in the drawings, the numeral 5 indicates a 30 violin or instrument of the viol type. The numeral 6 indicates the strings which pass in the usual way over the bridge 7. Above each string in a suitable position is a sounder or bow member 8, preferably of the type 35 described in my prior Patent No. 855,021, dated May 28, 1907. These sounders or bow members are mounted on the rotating supports or shaft 9, which are constantly driven from a bow motor, in the manner described 40 in my prior patent. The sounders or bow members 8 are, when not playing, some distance above the corresponding strings 6, as indicated clearly in Figure 2. The depression of the shafts 9 and of the corresponding 45 bow members or sounders is effected by means of the levers 10 which extend over the violin and are pivoted upon a shaft 11 mounted on the back 12 or other suitable support positioned at one side of the strings.

The ends of the levers 10 extending away 50 from the strings are provided with depending projections 13 which are preferably electro-magnetically actuated to cause the depression of the ends of the levers en- 55 gaging the sounder shafts 9. In the form

illustrated, alternating current electro-magnets 14 are employed, the cores of which are normally dropped to the lowermost position permitted by the tubes 15 depending from the electro-magnets. When the electro-magnet corresponding to any particular string is energized the core is brought to the center of the electro-magnet and, in rising, engages the projection 13 of the lever 10 and lifts it, causing the opposite end of the lever to depress the corresponding sounder shaft 9. The rotating sounder thereupon engages the string and produces the desired note.

The electro-magnets 14 are supported in 70 a frame 16 secured to the bracket 12. The spring 17, extending from the projection 18 back of the pivot of each of the levers to a suitable lug 19 on the bracket 12, tends to retract that end of the lever and to 75 thereby raise the opposite end, with the corresponding bow shaft, from the strings.

A preferred form of engagement of the ends of the levers 10 with the sounder shafts 9 is most clearly illustrated in Figure 2. 80 Each lever 10 is provided with a downwardly projecting ear or lug 20 in which is formed a lengthened slot 21. The corresponding bow shaft 9 passes through this slot. A slotted plate 22, preferably of elliptical form, passes over the ear 20 and is rigidly secured to the lever 10. A second slotted plate 23 of similar form likewise passes over each ear 20 and is freely movable therein. The slotted plate 23 is positioned above the sounder shaft 9 passing through the slot 21. Between the plates 22 and 23 is mounted a coil spring 24. When the bow end of the lever 10 is depressed by the actuation of one of the electro-magnets 14, it acts through the spring 24 and the plate 23 upon the corresponding sounder shaft 9 to depress the latter. It will thus be apparent that a resilient pressure is maintained upon each sounder shaft 9 in causing the playing of notes upon the corresponding string.

In playing the instrument, it is frequently desirable, and in staccato playing it is necessary to effect a quick and positive removal 105 of the sounders or bows from the strings independently of the action of the electro-magnets 14. In the present device, this is effected by actuation of the electromagnet 25, indicated in the drawings as an alternat-

ing current electromagnet. This electromagnet will suitably be supported in the same frame 16 as the electromagnets 14. Its freely movable core is normally held in a 5 raised position by the spring 26, supported at one end by the rigid frame 16. At its other end the spring 26 engages and tends to draw upwardly the plate 27 which is slidably mounted at one end on the guide 28. 10 The core of the electromagnet 25 is provided with a downwardly projecting portion 29 which passes through a guide-opening 30 in the plate 27. The core of the electromagnet 25, which is enlarged above its lower portion 29, normally rests upon the plate 27, a 15 felt bushing 31 being interposed. It will be apparent that the action of the spring is to maintain the core of the electromagnet 25 in its raised position. At its upper end 20 the core of this electromagnet is provided with a smaller extending portion 32 to which is secured a transverse plate 33 by means of a set-screw 34. On its under side the plate 33 is provided with a felt packing 25 35. The levers 10 are each provided with flattened end portions 36 which extend under the plate 35. It will be apparent that downward movement of the plate 35 will depress the ends 36 of any of the levers 10 30 that may be raised and will thereupon raise the opposite ends of the levers 10 and with them the corresponding sounder shafts 9. In the operation of the instrument, the 35 electromagnet 25 is energized by any suitable means, for example, a perforation in a music-sheet, at the moment when a staccato effect or a sudden lifting of the sounders in action at the time from the corresponding strings is desired. The electromagnet 25 is 40 preferably built so as to be more powerful in its action than the electromagnets 14 and it consequently produces its desired effect regardless of whether any of the electromagnets 14 are energized.

I claim:

1. In a self-playing musical instrument of the viol class, a plurality of rotating sounders corresponding with the strings of the instrument, a lever for bringing each of said sounders into engagement with its string, an electromagnetic device for actuating each of said levers to effect such engagement, and an electromagnetic device operative to retract said levers to effect complete disengagement of the sounders from their strings. 50 55

2. In a self-playing musical instrument of the viol class, rotating sounders corresponding to the strings of the instrument, a lever corresponding to each of said sounders, said levers being fulcrumed at one side of the strings of the instrument, means at one end of each of said levers for operating the corresponding sounder, an electromagnet for engaging the other end of each of said levers to actuate it and thereby bring the corresponding sounder into engagement with its string, an independently operable electro-magnet and a plate extending transversely across the ends of said levers and operated by the last mentioned electro-magnet to simultaneously engage the levers and thereby disengage the sounders from the strings. 60 65 70 75

3. In a self-playing musical instrument of the viol class, a plurality of rotating sounders corresponding with the several strings of the instrument, levers adapted to move said sounders with relation to the strings, springs acting on said levers and tending to hold the sounders away from the strings, electromagnets adapted to actuate the levers to cause the sounders to engage the strings, and a controlling magnetic device adapted to actuate said levers to effect complete removal of the sounders from the strings when a staccato effect is desired. 80 85

HENRY K. SANDELL.
